METHOD AND APPARATUS FOR PRODUCING
MUSICAL SOUNDS

Earle L. Kent, Chicago, Ill.

Application October 21, 1939, Serial No. 300,683

19 Claims. (Cl. 84—1.28)

My invention relates to a method and apparatus for producing musical sounds, and more particularly to a new electronic method and apparatus whereby organ-like musical instruments may be achieved.

Heretofore in the electronic musical instruments of the prior art, it has been necessary to produce tones by means of individual generators in order to obtain the desired timbre at each different pitch. Every musical note has two distinctive qualities, namely, its timbre, depending upon the instrument which produced it, and its pitch. Any means for producing a harmonic vibration of a given pitch possessing the characteristic wave shape of a violin, will produce a violin tone. It is possible to produce any desired wave form by synthesis, but it is necessary to have a plurality of synthesizing means to obtain the desired pitch.

Electrical engineers have for some time been cognizant of means of producing multiples or submultiples of a given wave by means of the relaxation oscillator, rectification and the like. I have found that I may change the frequency of a given wave, simple or complex, as for example a wave of one pitch having a predetermined desired timbre to a new frequency, and retain the same wave form as the original wave.

It will be apparent to those skilled in the art, for example, if diapason tones are desired I may, according to my invention, provide a single diapason generator and furnish tones at any audible pitch or any combination of pitches. The musician may sound diapason "C," "C $\sharp$," D and the like, independently or together in any combination, from the same diapason generator.

Similarly, I may by my method and apparatus, provide an instrument having any desired number of generators for generating musical timbres of known instruments or of new qualities, and convert them into any desired pitch or combination of notes having a plurality of desired pitches.

The advantages of such an instrument will be apparent. The complexity of an instrument made according to my invention is reduced, and its flexibility tremendously increased. For example, if it were desired to produce an organ having 1860 pipes (individual tone producers), to generate 20 different tone qualities for 32 pedals and 61 keys, such an instrument could be made using my invention with only 113 tone producers as compared with 1860.

One object of my invention is to provide a novel method of producing musical sounds.

Another object of my invention is to provide a novel apparatus for producing musical sounds of any desired pitch and timbre.

Another object of my invention is to provide 5 a novel electronic musical instrument.

Another object of my invention is to provide a novel electronic musical instrument in which standard and easily obtainable radio parts are employed.

10 Another object of my invention is to provide an electronic musical instrument in which the circuits are not critical and their adjustments can be made by any person having knowledge of radio repair, without special apparatus or skill.

15 Another object of my invention is to provide an organ-like electronic musical instrument in which standard stop controls may be used.

Another object of my invention is to provide 20 an organ-like electronic musical instrument in which the harmonic content may be varied or synthesized to suit the taste of an individual and in which a large number of different stops may be easily obtained.

Another object of my invention is to provide 25 a musical instrument in which a tone of any given timbre and pitch may be changed to another tone of the same timbre and of a different pitch.

Another object of my invention is to provide 30 an electronic musical instrument in which every tone produced has true harmonics and not tempered harmonics.

Another object of my invention is to provide 35 an electronic musical instrument in which every tone of the scale may have exactly the same quality or harmonic content, or may be made to vary somewhat from octave to octave in order to obtain the same quality variations as are present in other musical instruments.

40 Another object of my invention is to provide a musical instrument in which the entire instrument may be given a vibrato or combined vibrato and tremolo with a single vibrating means.

Another object of my invention is to provide 45 a novel musical instrument in which the vibrato may be applied to individual manuals or to the pedals.

Other objects of my invention will appear from the following description.

50 In the accompanying drawings which form part of the instant specification and which are to be read in conjunction therewith, and in which like reference numerals are used to indicate like parts in the various views:

55 Fig. 1 is a schematic view of one form of fre-

quency changer which enables me to apply a complex wave at a particular fundamental frequency and sine waves of other frequencies to obtain waves of different frequencies whose wave shapes conform with the shape of the original applied complex wave.

Fig. 2 is an end view of the cathode ray tube shown in Fig. 1.

Fig. 3 is an oscillogram taken with no complex wave applied to the cathode ray tube of Fig. 1, representing a curve of voltage against time.

Fig. 4 is a diagrammatic view showing a complex wave plotted against time with relative positions of the probe.

Fig. 5 is a schematic view of a frequency changer circuit capable of producing the results produced by the circuit of the apparatus shown in Fig. 1.

Fig. 6 is an oscillogram similar to Fig. 3, showing unidirectional pulses produced by the circuit of Fig. 5 with no complex wave applied.

Fig. 7 is a schematic view showing a stop control for producing predetermined timbres.

Fig. 8 is a curve showing voltages applied to the grid of the frequency changing tube, and the resultant curve of plate current.

Fig. 9 is a schematic view showing the vibrato and tremolo producing means.

Fig. 10 is a schematic view of a portion of an organ showing the relative location and connection of parts.

Fig. 11 is a schematic view showing the method of keying pulses employing a single frequency changer tube with a plurality of pulse generators.

Fig. 12 is a fragmentary detail view showing one method of keying.

Fig. 13 is a sectional view taken on the line 13—13, Fig. 12.

Fig. 14 is a sectional view taken on the line 14—14, Fig. 13.

Fig. 15 is a schematic view showing an instrument in which the human voice may be employed to initiate the complex wave.

In general, my invention contemplates the provision of a musical instrument in which a complex wave of any desired wave form is continuously generated and this complex wave changed in its frequency to obtain the desired pitch.

More particularly, referring to Fig. 1, a cathode ray tube 1 is provided with the usual cathode 2, a grid 3, a first anode 4 and an accelerating anode 5. There are two sets of deflecting plates 6 and 7 disposed at right angles to each other. The end of the tube is provided with a collecting ring 8 and a probe 9, the end of the tube 10 being provided with the usual fluorescent screen. The cathode is heated by battery 11.

Negative potential from battery 12 is impressed by conductor 13 upon the grid 3. The anode 4 is connected by conductor 14 to the positive terminal of battery 15. Battery 16 is connected in series with battery 15, and its positive terminal is connected by conductor 17 to the accelerating anode 5. A vacuum tube oscillator 18, of any suitable type, is adapted to generate a high frequency potential in the form of a sine wave. The output of the vacuum tube oscillator 18 is impressed across deflecting plate 6 through an inductance 19, and across deflecting plate 7 through a capacity 20. The inductance and capacity are such that the voltage impressed on deflecting plate 6 is 90° out of phase with the voltage impressed across deflecting plate 7. Considering now the action of the cathode ray tube, let us assume that the complex wave generator 21 is generating

a sine wave. Then the voltage applied to the grid e_g may be represented by the expression

$$e_g = A \sin 2\pi f' t.$$

Disregarding the D. C. bias applied to the grid for the sake of simplicity, the intensity of the electron beam i_b may be represented

$$i_b = A' \sin 2\pi f' t.$$

If the cathode ray beam is focused on the end of the tube by the usual procedure, and the beam moved by the application of voltage x

$$x = B \cos 2\pi f' t$$

applied to the vertical plates, and by the voltage y

$$y = B \sin 2\pi f' t$$

applied to the horizontal plates, the beam will move in a circle.

Every time the beam strikes the probe 9, the electrons will be given off by secondary emission which are collected by the collector 8. The voltage between the secondary emitter 9 and the collecting ring 8 will be a unidirectional voltage in the form of pulses.

Since we have neglected the D. C. component of the beam, the generated voltage between the secondary emitter and the collector may be expressed by the expression

$$e_p = k i_b F(f' t)$$

where k is a constant, i_b is the intensity of the electron beam, and the expression $F(f' t)$ is a function of $f' t$.

With the probe 9 in the position shown in Fig. 35, e_p will have a value only when y equals zero, and x is positive. So, $F(f' t)$ might be defined as $\cos 2\pi n$ where $n=0, 1, 2, \dots$ and also $n=f' t$ then,

$$e_p = k i_b \cos 2\pi n = A \sin 2\pi f' t \cos n 2\pi.$$

From the above equation we obtain a series of discrete values every time $f' t = n = 0, 1, 2, 3, \dots$, and of course the usual voltage would be the average of these discrete values. It would be 45 equally correct on the other hand to define $F(f' t)$ so that

$$e_p = A \sin 2\pi f' t \cos 2\pi n - A \cos 2\pi f' t \sin n 2\pi.$$

since the last term is always zero when the equation is evaluated. Since $n=f' t$ we may write

$$e_p = A \left[\sin 2\pi \frac{f'}{f_1} t \cos 2\pi n - \cos 2\pi \frac{f'}{f_1} t \sin 2\pi n \right]$$

and by trigonometric identity,

$$e_p = A \sin 2\pi \left(\frac{f'}{f_1} - 1 \right) n$$

It will be apparent from the foregoing equation that the voltage generator will be a series of discrete values whose average can be seen to be a sine wave whose frequency is equal to $f' - f_1$, and whose peak value will be proportional to the peak value of the voltage applied to the grid, and independent of the peak value of the voltage applied to the deflecting plates. It must be remembered that the voltage is unidirectional and can have no reversal of direction as the above equation indicates, but if the D. C. component had been carried along through this derivation the physical significance of the equation would be at once apparent.

If no signal was applied to the modulating grid 3, the electron beam would be deflected in a circle. Every time the beam of electrons hit the secondary emitter 9, it would cause the probe to

emit electrons which are collected by the collecting ring 8. The potential difference between the probe and the collecting ring may be amplified by the vacuum tube 22, the output of which tube is loaded so that any rapid changes in potential of the plate 23 are practically prohibited by the condenser 24. High frequency signals are blocked by the choke coil 25 from going to the grid 26 of the vacuum tube 27. It will be seen that with no signal applied to the modulating grid 3, that the pulses of the voltage between the probe and the collector will be of uniform height proportional to the beam current at the time it strikes the probe.

With the amplifying arrangement shown, the occurrence of the pulses in rapid succession and at the same magnitude will result with no signal output across points 28 and 29 of the amplifier. If we apply a simple alternating potential to the grid $e_0 = A'' \sin 2\pi f't$, as pointed out above, the intensity of the electron beam i_b may be expressed by

$$i_b = A' \sin 2\pi f't + K$$

Let us consider that the frequency of the signal applied to grid 3 (f') is equal to the frequency of the signal applied to the deflecting plates 6 and 7 (f_1). In such case when the beam sweeps in a circle on the end of the cathode ray tube 1, the circle of light would be a stationary pattern of sinusoidal distribution such as shown in Fig. 2, in which the portion 30 would be of maximum brightness, the portion 31 of half brightness, and the portion 32 of minimum brightness.

The equation of the circle on the end of the tube 9 is as follows

$$p(x,y) = B \cos 2\pi f_1 t + jB \sin 2\pi f_1 t$$

And we can see from the above equation that the position of the point where the cathode ray spot is at any time, t . We are interested primarily, however, in knowing at what time t is the spot or point $p(x,y)$ at the probe and the above equation tells us the $p(x,y)$ will be at the probe at whatever values of t will make $jB \sin 2\pi f_1 t = 0$. Furthermore $jB \sin 2\pi f_1 t$ will equal zero if $f_1 t = n$ where n is any positive integer.

From this relation we can determine the value of the intensity of the beam at the time it hits the probe, thus

$$\begin{aligned} i_b &= A' \sin 2\pi f_1 t + K \\ &= A' \sin 2\pi n + K \quad (\text{since } f' = f_1) \\ &= A' 0 + K \end{aligned}$$

where K is the beam intensity due to the battery 12 and is the steady component above and below which the alternating component operates.

If $i_b = K$ every time the cathode ray hits the probe the pulses will all be of the same magnitude and the signal output across points 28 and 29 will be zero. An oscillogram of the pulses of voltage taken across the probe 9 and collector ring 8 is shown in Fig. 3.

Let us now consider another case where f' is slightly greater than f_1 in which case the circle of light would no longer be stationary but would rotate clockwise. This is because i_b reaches a maximum value before it reaches the top of the circle (Fig. 2) after one revolution of the beam and as this process continues the sinusoidal pattern of light appears to move in the clockwise direction.

When there is relative motion between the probe and the pattern the value of i_b will not always be the same but after the pattern has

made one revolution the variation in voltage of the pulses will have gone through one cycle.

To be more specific take as an example a case where

$$\begin{aligned} f' &= 101,000 \text{ cycles per second} \\ f_1 &= 100,000 \text{ cycles per second} \end{aligned}$$

where the beam would make one revolution on the end of the tube 1 in .00001 sec. but it goes through a cycle of values in $\frac{1}{10000}$ sec. and therefore the pattern will advance .01 rev. in the clockwise direction every time the beam goes around. Since the beam goes around 100,000 times in one sec., the pattern will make $100,000 \times .01 = 1000$ revolutions per second.

With these values for f' and f_1 we will get 100,000 pulses at the probe in one second but they will not all be of the same magnitude because it is not always at the same value when it hits the probe. We can see in fact that since the pattern is moving with respect to the probe as it is, that the height of the pulses will go through sinusoidal variations 1000 times per sec.

While condenser 24 offers a low impedance to a pulse frequency of 100,000 cycles per second, it will be a high impedance to the variation in average pulse height which occurs at the rate of 1000 cycles per second, so that the 1000 cycle per second variations will appear at the grid 26 of the tube 27 and hence across the output 28 and 29.

When the difference between f' and f_1 is small compared to f_1 the equation

$$f = \frac{v - V}{\lambda}$$

35 may be written $f' - f_1$, in which—

v =velocity of the beam variations

V =velocity of the beam

λ =wave length

f =frequency at output 28 and 29

That the above equation does not completely interpret our physical conditions can be seen if we make,

$$f' = 200,000 \text{ C. P. S.}$$

$$f_1 = 100,000 \text{ C. P. S.}$$

in which case the i_b would undergo exactly two sinusoidal variations while the beam made one revolution on the end of the tube and therefore would give a standing pattern as before except that now our circle of light would have two maximum points and two minimum points. There would be no signal at output 28 and 29 since there is no relative motion between the pattern and the probe. Yet the above equation indicates $f = 100,000 \text{ C. P. S.}$ So we might express the equation as follows, $f = f' - f_1 m$ where m =integer representing the number of waves in the rotating pattern, then $f = 200,000 - 100,000 \times 2 = 0$.

Suppose now that we apply to grid 3, Fig. 1,

$$e_0 = A_1'' \sin 2\pi f't + A_2'' \sin 4\pi f't$$

which will modulate the intensity of the electron beam

$$i_b = A_1' \sin 2\pi f't + A_2' \sin 4\pi f't$$

and for example let us assign the following values:

$$f' = 100,000 \text{ C. P. S.}$$

$$f_1 = 100,000 \text{ C. P. S.}$$

which will give us a stationary pattern on the end of the tube and the pattern will consist of a fundamental wave and a second harmonic. Since the pattern does not move with respect to the

probe there is no signal at output 28 and 29. Then consider,

$$f' = 101,000 \text{ C. P. S.}$$

$$f_1 = 100,000 \text{ C. P. S.}$$

which will cause the fundamental pattern to rotate as pointed out above at 1000 revolutions per second but the second harmonic will pass the probe twice as often or 2000 R. P. S. The rotation of the pattern will cause variations in pulse heights that will give a signal at output 28 and 29 made up of a fundamental whose frequency is 1000 C. P. S. and whose amplitude is proportional to A_1 plus a second harmonic whose frequency is 2000 C. P. S. and whose amplitude is proportional to A_2 . In other words, the signal at output 28 and 29 is

$$e = A_1 \sin 2\pi f t + A_2 \sin 2\pi f t$$

It will be understood, of course, that the circle of light does not exist as such, but is rather the result of the persistence of vision and the persistence of the screen itself. The electric circuit, however, makes the instantaneous values appear as average values across the output 28 and 29, and therefore evaluates them much the same as our eye does the moving spot of light caused by the fluorescence of the screen under the impact of the cathode ray.

It will be understood that my frequency changing principle makes use of an electrical effect analogous to the Doppler effect in sound. The relative motion of the probe to the revolving electron beam modifies the frequency of voltage variations in the electron beam, and may be expressed as follows:

$$f = \frac{v - V}{\lambda}$$

in which

v = the velocity of the electric wave
 V = the relative velocity of the probe
 λ = the wave length of the wave, and
 f = the frequency of the wave experienced by the probe

It will be observed that in my method for producing an electrical effect analogous to the Doppler effect I make use of a cathode ray tube, but my method is not to be confused with systems using cathode ray tubes for the generation of signals in which the output is dependent upon the shape or material of the object being scanned by the electron beam for the wave shape and frequency.

Let us now consider the case where the voltage applied to the grid 3 (A) is not a simple sine wave, but has a second harmonic

$$e_3 = A_1' \sin 2\pi f' t + A_2' \sin 4\pi f' t$$

then

$$i_b = A_1' \sin 2\pi f' t + A_2' \sin 4\pi f' t$$

and

$$e_p = A_1 [\sin 2\pi f' t \cos 2\pi n - \cos 2\pi f' t \sin 2\pi n] + A_2 [\sin 4\pi f' t \cos 4\pi n - \cos 4\pi f' t \sin 4\pi n]$$

$$= A_1 \sin 2\pi \left(\frac{f'}{f_1} - 1 \right) n + A_2 \sin 2\pi \left(\frac{2f'}{f_1} - 1 \right) n$$

It will be clear from the foregoing equation that we will obtain a generated voltage whose fundamental has a peak value dependent only upon the peak value of the fundamental applied to the

grid, and further, a second harmonic whose peak depends upon the peak of the second harmonic applied to the grid. It will be readily understood by those skilled in the art that a complex wave with any number of harmonics can be treated in the same manner as the simpler waves.

Thus far we have considered only cases in which sine waves were applied to the deflecting plates 6 and 7. If we are to produce a musical instrument, we must be able to produce more than one note at one time from the same tube.

I can apply a multiplicity of sine waves to the deflecting plates and obtain a corresponding number of complex waves. The physical concept 15 of the mechanism of this operation is much more difficult to visualize than the simple case, since in this instance the electron beam no longer travels in a true circle at the end of the tube.

The fundamental basis of my invention is not 20 limited to any specific piece of apparatus. It will be observed that the cathode ray tube is used in the embodiment shown in Fig. 1 to generate a plurality of pulses at predetermined frequency, the pulses being sharp, that is, the width 25 of each pulse is narrow as compared to the distance between pulses. When the height of the pulses is the same, no output will be obtained from the amplifier. Upon this pulsing current I impose a modulating current having any desired 30 wave form. The result of the superimposition of the modulating current will be a series of pulses whose envelope will describe a wave whose frequency is a function of the difference between the frequency of the modulating wave and the 35 frequency of the pulses. The form of the envelope, furthermore, will be the form of the modulating wave.

Any means, therefore, of producing a plurality 40 of pulses of uniform height and at a given frequency may be used as the basis upon which to impose the modulating current to obtain a current having a form identical to the modulating current form, but at a new frequency depending upon the frequencies of the pulses and the modulating current. The result will be the equivalent of that obtained with the cathode ray tube arrangement just described.

Referring now to Fig. 4, the curve 33 represents the voltage plotted against time t . If the wave 33 is probed or scanned at a frequency which is the same as the frequency of the wave 33, the probe, which is represented by the reference numeral 34, will remain stationary at full line position, and will experience no voltage variations. If, however, the probe is moved in the x direction, within a time $t + \Delta t$, to a position shown by the dotted line 35 in Fig. 4, and within a time $t + 2\Delta t$ to a position shown by the dotted line 36 in Fig. 4, and so on at the same rate, then the probe will experience voltage variation that is the same as the wave shape of the voltage distribution but at a different frequency than if it had no relative motion. It will be clear that the effect is equivalent to the Doppler effect in sound, which 65 may be observed by the sudden change in pitch of the whistle or bell of a passing train. The change in pitch is due to the relative motion of the sound source with respect to the ear.

Another embodiment of my invention is shown 70 in Fig. 5, in which I employ a "feed-back" oscillator and a mixer tube.

Referring now to Fig. 5, the tube 37 is a double triode acting as a feed-back oscillator to create sharp positive pulses at the grid 38 of tube 39. The tube 39 is a pentagrid mixer amplifier tube.

The grid 38 is normally biased negatively so that the tube 39 is at "cut-off" and no plate current flows in it. However, the positive pulse applied to the grid 38 causes the plate current to flow in tube 39 in sharp pulses. The wave whose frequency is to be changed is applied to the grid 40 of the tube 39. Since all pulses applied to the grid 38 are of equal magnitude the plate current pulses will also be of equal magnitude if the voltage on grid 40 is not varied. Then, too, if the complex wave applied to the grid 40 is of the same frequency as the pulses applied to the grid 38, the plate current pulses of the output of tube 39 will be of the same magnitude since the grid 40 would then be always at the same voltage when the pulses occur.

It will be observed that the tube 39 acts as a sampler to evaluate the voltage on the grid 40 at predetermined intervals.

Fig. 6 shows an oscillogram of the pulses generated by the tube 37. It will be noted that this oscillogram is substantially the same as that shown in Fig. 3 which is the oscillogram of the pulses obtained from the cathode ray tube in the arrangement in Fig. 1.

The sampling or scanning action is shown graphically in Fig. 8. When the tube 37 has a "B" voltage of, for example, 100 volts, applied to the plate 41, a large plate current will flow since the grid 42 is connected to a positive point 43 on the "B" battery 44. The flow of current from plate 41 to cathode 45, to the negative terminal 46 of the battery 44 is through a resistance 47. The voltage drop across the resistance 47 biases the tube 37 and causes a decrease in the plate current flow. The drop in the plate current occurs rapidly, causing a sharp rise in voltage across the plate resistor 48. This positive pulse is impressed upon the grid 49, where it undergoes a 180 degree phase change with amplification and is sent as a negative pulse to the grid 42, where it drives the grid to "cut-off" and plate current ceases to flow from plate 41 to cathode 45. The voltage across resistor 47 will quickly discharge through condenser 50 since the time constant of resistor 47 and the condenser 50 is very small.

When the voltage across resistor 47 falls far enough to permit plate current to flow again in the plate circuit of plate 41, the cycle is repeated. The values of the resistors and the condensers are such that very narrow positive pulses are created across the resistance 48, which pulses are impressed upon the grid 38 of tube 39 through conductor 51. The resistor 52 has considerable influence upon the frequency at which the circuit will oscillate, and this will be more fully discussed hereinafter. The other resistors and condensers have some effect on frequency, but they should be chosen so as to give the sharpest pulse near the desired frequency. The resistor 52 can then be relied upon to adjust the frequency over a relatively wide range with a minimum effect on the width of the pulse. The exact frequency at which the circuit oscillates is controlled by the introduction of pulses at point 53, as will be pointed out hereinafter. If the resistance 52 is set so that the circuit will oscillate slightly slower than is desired, then upon the introduction of positive pulses of exactly the correct frequency upon the grid 49 across points 53 and 54, these pulses will be amplified by the left hand section of tube 37 and arrive at the right hand section of tube 37 to force it to cut-off if it is near the cut-off value. If the frequency of the pulses

applied across points 53 and 54 is double the frequency at which the circuit would normally operate, then every other pulse will reach the grid 42 at a time when it is not near enough to cut-off value to "trip" the circuit, but the other pulses would be effective.

Generally feed-back oscillators of the type shown are not sufficiently stable to operate dependably at a given frequency unless they are held at that frequency by a stable signal whose frequency is the multiple of the frequency desired from the oscillator. An oscillator of this type, however, is desirable in my invention because of its simplicity and because it gives the properly shaped pulses employed in my frequency changer and frequency changing method.

Referring again to Fig. 5, tube 55 is a pentode used as an electron-coupled oscillator with high frequency stability. It will be understood, of course, that an oscillator of any design could be used, provided it was sufficiently stable at the desired frequency. Furthermore, if desired, a crystal controlled oscillator could be employed since the oscillator operates at radio frequency. This is a point of great advantage over the electronic instruments of the prior art whose oscillators operate at audio frequency. The oscillator may operate at any desired frequency, say, for example, 100,000 cycles per second, or some multiple thereof. In this case the twin triode tube 37 acting as a feed-back oscillator would be tuned to oscillate at slightly less than 100,000 cycles per second. The output of the tube 55 is impressed across points 53 and 54 by means of transformer 56. The impression of the output of the oscillator 55 across points 53 and 54 will lock the tube 37 to the frequency of oscillation of the tube 55, since the signal of the tube 55 will be impressed across points 53 and 54.

The arrangement is such, therefore, that the output of tube 37 will be narrow pulses at the frequency of the control tube 55, that is, 100,000 cycles per second. This output will be applied, as pointed out above, to the grid 38 of tube 39.

A complex wave whose frequency is to be changed is applied to the grid 40 at point 57, the other side of the output being grounded. The complex wave may be generated in any suitable manner, one of which will be pointed out hereinafter.

Let us assume that the complex wave has a frequency of 101,046,502 cycles per second, and this is applied to the grid 40 of the tube 39 through point 57. Tube 39 acting as a frequency changer will create in its plate circuit 100,000 pulses per second and these pulses will vary periodically in magnitude 1046.502 cycles per second with an envelope whose wave form is identical with the complex wave applied to the grid 40. A wave whose frequency is 1046.502 cycles per second is C₈ in the musical scale.

The tube 39 will function if it has the proper bias. The bias of this tube is controlled in the diagrammatic view of Fig. 5 by the key 58. Key 58 is normally against the stop 59 and makes contact with 60 if the cam 61 is in the position shown. When the key 58 is in the up position against stop 59, the grid 40 of the tube 39 is biased to "cut-off" by the battery 62. It is biased to cut-off regardless of the position of the cam 61. When the key is pressed down toward stop 63 it makes contact with contact points 64 and 65 simultaneously if the cam 66 is in the position shown. If the switch 67 is in contact with contact point 68, there is enough positive potential

from battery 69 to bring the grid 48 of tube 39 to a low enough negative potential for the tube to be properly biased when the pulses occur. When the key 58 is released and comes into contact with contact point 60, the voltage across condenser 70 is lowered to bias the tube again to cut-off. The condenser 70 is in this case charged through resistor 71 and the time constant of resistor 71 and condenser 70 is such that the condenser 70 charges quickly but not abruptly. It is fast enough for a standard release of tone, but not fast enough for a click or thump effect. If the cam 61 is turned so that the key 58 cannot contact contact point 60 when it is released, then the condenser 70 must take its charging current through the resistor 71 and resistor 72 in series, thus increasing the time constant. The resistor 72 is large enough to cause the tone to decay sufficiently slowly to make string tones sound like plucked strings, chime tones to sound like chimes, and bell tones to sound like bells.

Cam 61 is operated by a pedal and the shaft 73 upon which it is mounted may run the full length of the key manual. Cam 66 is mounted on shaft 74 and it may be moved to three positions. In one position contact points 64 and 65 are normally in contact so that when the key 58 is depressed it makes contact with both these contact points as a unit, and the resistor 75 allows charging current to build up a less negative voltage across the condenser 70 quickly but not fast enough for key thumps. The second position to which cam 66 may be moved separates contact points 65 and 64 so that they will close in sequence when the key 58 is depressed, giving "second touch" which will be explained more fully hereinafter. The third position to which cam 66 may be moved is to depress contact point 65 downwardly so that the key 58 will contact only contact point 64 when pressed. In the third case the charging current for condenser 70 must flow through resistances 76 and 75 in series. This gives the notes a slower attack which is desirable for legato passages of music. It will be observed these combinations for different attack and release of notes offers all that a musician really needs and gives a maximum utility with a small number of parts and contacts.

When cam 66 is in the second position, that is, with contact points 64 and 65 separated but in such a position that contact will be made with contact points 64 and 65 in succession, if the key 58 is pressed only part of the way down, it makes contact with contact point 64 and brings the bias of tube 39 to an operating region at a relatively slow rate of attack. If the key, however, is pressed further, so as to make contact with both contact points 64 and 65, the bias is made less negative quickly and the resulting tone will be louder because of this change in the operating point of the tube 39. The cam 66 can be so shaped and located that when it pushes contact point 65 into the second position, it may still rest against the bottom of contact point 64, serving as an index to the musician because extra pressure will be required to make the further contact with contact point 65. In this manner the musician may play lightly and put emphasis on some notes by more pressure, making them sound louder and "brighter." Quickly pushing the key down as far as it will go, gives a faster attack time as well as making the note sound louder than those not pressed quite all of the way. When the cam 66 is in the first or third positions, it has no effect upon the pressure

required to push the key down. The switch 67 may be arranged at the end of the shaft 74 in such a position that the switch 67 will contact contact point 77 when the cam is in the first position, and contact contact point 68 when the cam 66 is in the third position making it possible to change the attack time while keeping the operating bias the same in either position.

The operation of the arrangement can be 10 readily understood by reference to Fig. 8, in which i_p represents the plate current output of the frequency changer tube and e_g represents the grid voltage impressed upon the control grids of this tube. The curve 78 is a conventionalized 15 characteristic curve of the tube. The curve 79 represents the pulses generated by the pulse generator at a predetermined frequency. The curve 80 represents the complex wave whose frequency is to be changed. It will be noted that the positive pulses alone operate below the point of cut-off. It will be likewise noted that the complex 20 wave is below the point of cut-off. The pulse wave scans or samples the complex wave at a predetermined frequency, and due to the difference 25 of the frequency between the complex wave and the scanning wave, the output of the frequency changer will, by an effect analogous to the Doppler effect described above, produce a series 30 of pulses 81 which will vary periodically in magnitude at a frequency depending upon the relative motion of the scanning or pulse wave with respect to the complex wave, and whose envelope 82 will comprise a wave form exactly like the complex wave 80.

35 The timber of a musical note, that is, its wave shape, is governed by its harmonic content, and the relative amount of the various harmonics present. In order to obtain a complex wave 40 equivalent to a musical instrument or a plurality of musical instruments, I provide the arrangement shown in Fig. 7.

A radio oscillator of any suitable type capable 45 of generating waves at radio frequency and with a high harmonic content, is shown diagrammatically by the reference numeral 83. The oscillator 83 can be a feed-back oscillator, such as described above, to generate the pulses. The voltage pulses which comprise the output of the 50 complex wave generator 83 are applied at terminals 84 and 85 by conductors 86 and 87. Between terminals 84 and 85 are a series of tuned 55 parallel circuits 88, 89, 90, 91, 92, 93, 94, and 95. If, for example, the complex wave generator 60 were tuned to oscillate at 101,046.502 cycles per second, the parallel tuned circuit 88 would be tuned to this frequency, namely, 101,046.502 cycles per second. Circuit 89 would be tuned to the second harmonic or 202,093.004 cycles per second. Circuit 90 would be tuned to the third harmonic, or 303,139.506 cycles per second. Similarly, parallel tuned circuit 91 would be 65 tuned to the fourth harmonic; circuit 92 to the fifth harmonic; circuit 93 to the sixth harmonic; circuit 94 to the seventh harmonic; and circuit 95 to the eighth harmonic, and so on for every harmonic it is desired to control. The parallel tuned circuit 88 is short-circuited by a resistor 96. Parallel tuned circuit 89 is short-circuited by a resistor 97. Similarly, resistors 98, 99, 100, 101, 102 and 103 short-circuit tuned circuits 88, 91, 92, 93, 94, and 95, respectively.

70 It is understood, of course, that a tuned circuit offers a high impedance to waves of a frequency to which the circuit is tuned, while permitting the passage of waves of other frequen-

cies. With tuned circuit 88, across terminals 84 and 85 all of the fundamental will appear at point 107. If, however, tuned circuit 88 is short-circuited by the resistor 96, then none of the fundamental will appear across terminals 107 and 108.

The panel 109 represents the front of the instrument board of an instrument built in accordance with my invention. A plurality of control shafts 110, 111, 112, 113, 114, 115 and 116 are provided. Each of the shafts represents a stop, preferably arranged in accord with the standards of the American Guild of Organists. Each stop produces a complex wave of the desired timbre to represent the instrument. Taking stop 113 for example, it will be noted that the resistance 97 for the second harmonic is shunted, none of the second harmonic being present in the complex wave of stop 113. The resistance 98 across the parallel tuned circuit 90, tuned to the third harmonic, is shunted except for the portion embraced between points 117 and 118. The value of this resistance represents the portion of the fundamental which is present in the complex wave represented by the stop 113. It will be noted that the entire resistance 97 for the second harmonic is shunted, none of the second harmonic being present in the complex wave of stop 113. The resistance 98 across the parallel tuned circuit 90, tuned to the third harmonic, is shunted except for the portion embraced between points 119 and 120. That portion of resistance 98 embraced between points 121 and 122 represents the fourth harmonic component of the instrument represented by stop 113. None of the fifth harmonic is present in the complex wave of stop 113. That portion of the resistance 101 embraced between points 123 and 124 represents the sixth harmonic component present in the stop 113. None of the seventh harmonic is present in the complex wave of stop 113, while that portion of the resistance 103 embraced between points 125 and 126 represents the component of the eighth harmonic present in the stop 113.

It will be seen that the arrangement is such that none of the resistance is normally shunted with the stop controls pulled out. The pushing in of any stop produces a complex wave having a desired wave form. Its harmonic content can be precalculated to produce a complex wave of any desired timbre. Stop 110, for example, may produce the complex wave of a French horn. Stop 111 may produce the characteristic wave form of a diapason. Stop 112 may produce a complex wave which has the wave form of a violin tone. Any desired complex wave may be synthesized by the proper adjustment of the harmonic content.

If it is desired to synthesize tones the stop 116 is pulled out. This shunts the resistances to amounts depending upon contact arms 127, 128, 129, 130, 131, 132, 133, 134. These contact arms may be contact arms of potentiometers operating on the respective resistances. In this manner harmonic values may be added or subtracted to synthesize a complex wave having any desired timbre.

It is understood, of course, that any suitable number of synthetic stops 116 may be employed in which the individual potentiometers may be pre-set and the synthesized tone brought into place by the operation of the shaft 135 through the stop 116.

It will be seen from the arrangement in Fig. 7 that we may obtain a complex wave of desired wave form provided the complex wave generator is one which will produce a wave rich in harmonic content. Inasmuch as the complex wave

generator 83 is a feed-back oscillator, such as shown in Fig. 5, the pulses produced will be of the shape shown in Fig. 6. The harmonic analysis of a wave of the shape shown in Fig. 6 shows that it may be expressed as follows:

$$\frac{a}{\pi} + \frac{2}{\pi} \sum_{n=1}^{\infty} \frac{\sin na}{n} \cos nwt$$

10 where

$2a$ =width of pulse with respect to the length of a cycle

n =a positive integer

$w=2\pi$ times the frequency

15

This expression shows that when the width of the pulse is small compared to the length of the cycle the wave contains essentially an equal amount of harmonics. As an example if $2a=.01\pi$ the harmonics in the wave would compare as follows:

Fundamental	= 1.0
2nd harmonic	= 1.0
3rd	= 1.0
4th	= 1.0
5th	= 1.0
6th	= .999
7th	= .998
8th	= .997
9th	= .996
10th	= .996
20th	= .987
30th	= .962

35

It is possible, therefore, to produce any desired wave form at terminals 107, 108 by having a tuned circuit and a voltage divider for every harmonic that it is desired to control. Of course if it is not desired to have absolute control over each harmonic contained in the wave, a less complicated filter may produce a variety of tones that may be desired. However, since only a few of such filters is needed for the entire instrument it seems desirable to be able to synthesize any desired tone.

40

It is desirable too, to arrange the controls of the instrument in accord with the standards of the American Guild of Organists since so many of the musicians who would be apt to play this instrument have spent many hours practicing with organs that meet these standards.

45

Referring again to Fig. 5, it was assumed that pulses of a frequency of 100,000 cycles per second were applied to the grid 38 and the complex wave applied to the grid 40 was at a frequency of 101,046.502 cycles per second, thereby producing in the output circuit a wave whose frequency was 1046.502, which is C₅ in the musical scale. Another feed-back oscillator such as shown by tube 37 in Fig. 5, and associated frequency changer produces the note C₄ in the musical scale. Its feed-back oscillator may operate at 50,000 cycles per second and is synchronized or locked at this frequency by the 100,000 cycles per second pulses across the terminal 136 and ground of tube 37.

50

In an instrument according to my invention there would be another feed-back oscillator generating the pulse wave like that generated by the complex wave generator 83, but at half its frequency. For example, if the complex wave generator to produce note C₅ operated at a frequency of 101,046.502 cycles per second, the second complex wave generator would operate at a frequency of 50,523.251 cycles per second and would be held at this frequency by the synchronizing pulses

55

across point 137 and ground of Fig. 7. This second complex wave generator feeds a complex wave to the grid of another frequency changer tube producing C₃. This process is repeated for C₂, C₁, and C₀. It will be seen by virtue of this locking feature of the feed-back oscillators, all of the C's are exact octaves of each other. In this manner a complete instrument could be built up using 12 stabilized oscillators such as shown in Fig. 5, each controlling its series of feed-back oscillators. There are 6 feed-back oscillators for producing complex waves such as indicated diagrammatically by 83 in Fig. 7. These 6 feed-back oscillators would all be stabilized by the first oscillator.

Another way of building an instrument embodying my invention is shown diagrammatically in Fig. 10, in which a plurality of stabilized impulse generators are shown, one for each note of the scale. Three octaves are shown by way of example, namely, the zero, first and second octaves. Each octave employs a single frequency changer tube. The zero octave employs a frequency changer tube 138. The first octave employs a frequency changer tube 139. The second octave employs a frequency changer tube 140. A single stabilized complex wave generator 141 is employed. Each of the impulse generators is electrically connected to a key, a few of which are shown by way of example in Fig. 10.

- Key 142 controls the impulse generator B₂.
- Key 143 controls the impulse generator A#₂.
- Key 144 controls the impulse generator A₂.
- Key 145 controls the impulse generator G#₂.
- Key 146 controls the impulse generator G₂.
- Key 147 controls the impulse generator F#₂.
- Key 148 controls the impulse generator F₂.
- Key 149 controls the impulse generator E₂.
- Key 150 controls the impulse generator D#₂.
- Key 151 controls the impulse generator D₂.
- Key 152 controls the impulse generator C#₂.
- Key 153 controls the impulse generator C₂.

The complex wave generator is provided with the stop control shown in Fig. 7, and produces a complex wave at a predetermined radio frequency as, for example, 50,000 cycles per second. The complex wave of this frequency is impressed at all times upon the grid 154 of the tube 140, the grid 155 of the tube 139 and the grid 156 of the tube 138.

Since no scanning or pulse waves have been impressed upon the frequency changer tubes and the frequency changer tubes are all biased to operate below cut-off, no note will sound as long as none of the impulse generators may impress the output upon the grid 157 of tube 140, the grid 158 of tube 139, or grid 159 of tube 138.

When, however, a key is pressed the result of this action is such as to permit the complex wave to be scanned by the wave of the predetermined radio frequency, differing from the complex wave frequency by a number of cycles equal to the frequency of the pitch of the desired note. If two keys are pressed, the effect of course is that of two notes sounded in unison. Similarly, any number of notes can be sounded by the actuation of the corresponding number of keys.

All of the plate outputs of the frequency changer tubes are in parallel and feed into a transformer 160. The condenser 161 is of such value as to shunt frequencies above the audio range but permit the audio frequencies of the octave produced by frequency changer tube 140 to be unaffected. Similarly, the condenser 162

is of such value as to shunt frequencies above the audio range but permit audio frequencies of the octave produced by frequency changer 139 to be unaffected.

5 In an instrument having six octaves there will be six primary windings such as 163, 164 and 165. In each case the primary winding will be provided with a suitable by-pass condenser to shunt unwanted frequencies of the pulses and its harmonics while leaving the desired audio frequencies and their harmonics unaffected. It will be observed by those skilled in the art that these condensers make their windings broadly resonant to help in the frequency discrimination at the lower octaves.

15 The secondary winding of the transformer 166 feeds into an amplifier and volume control 167, which actuates loud speaker 168. If desired, the higher three octaves may be fitted with a transformer similar to that shown for the lower three octaves and fitted with an individual amplifier and volume control and loud speaker. Then, too, each octave may have its own individual loud speaker especially resonant to audio tones of that octave, so that truer sound effects may be achieved. The wealth and flexibility of an instrument according to my invention becomes apparent.

20 In Fig. 10 I have shown diagrammatically at 169 a vibrato. This is any means for producing a voltage at a low frequency which is applied in varying amounts to the grids 157, 158, and 159 of the frequency changer tubes 140, 139 and 138 through variable resistances 170, 171 and 172, 25 which may be operated by a common pedal, if desired.

25 Referring now to Fig. 9, I have shown an arrangement employing a gaseous discharge tube to produce a vibrato. The amplitude of the vibrato may be controlled by the variable resistance arm 173, or by the variable resistor 174 of Fig. 9. The switch 175 cuts the vibrato on and off. The frequency of the vibrato is controlled by the resistor 176.

30 The tube 177 is a typical stabilized oscillator. The gaseous discharge tube 178 causes the frequency of the oscillator tube 177 to shift periodically slightly from its normal frequency. The value of resistance 176 controls the frequency of the change. The arrangement will be readily understood by those skilled in the art by reference to Fig. 9. It will be understood that any suitable vibrating means, vibrating at a low frequency may be employed to introduce changes of voltage upon the screen grid 179 of the oscillator tube 177 to produce a vibrato effect.

35 If the tube 177 represents the complex wave generator 83 of Fig. 7, it will produce a vibrato effect to all of the tones produced by the instrument.

40 Tuned circuits 88, 89, 90, 91 and the like, are sharply resonant and the changing frequency therefore will also bring about a change in amplitude of the tones and their harmonics, giving a combination vibrato and tremolo effect. Furthermore, by controlling the shapes of the resonant curves of the tuned circuits 88, 89, 90 and the like, it is possible that the tremolo be greater on high tones than on low ones, and greater on the high harmonics of the tones than on the fundamentals.

45 If it is desired to give each of the twelve intervals of the scale a slightly different vibrato than others, the tube 177 may represent the

pulse generator, in which case obviously a differential vibrato may be achieved.

It will be observed that the resistance 180 upon which resistance arm 173 acts as a potential divider in the screen grid circuit of the tube 111, is so adjusted that the oscillator is not changed in frequency with changes in voltage supplied at B+ helping the frequency stabilization. Such an oscillator can, with temperature compensated tuned circuits, maintain commercially a frequency stability of 20 to 100 parts in a million, which is ample for tone fidelity.

I can very easily arrange a pedal or other control, for moving the voltage arm 173 either way from its optimum operating point. For example, if a rocking pedal is arranged so that it changes this tap, it being situated in a stabilizing oscillator of the complex wave generator, it makes it possible for the musician to slur up or slur down the tones which are produced since the pedal thus changes the frequency up or down. A catch on the pedal would tell the musician where to leave it for proper pitch and for the best voltage stability of the oscillator. If the instrument should be used with another instrument not tuned to International pitch, this pedal, obviously, could be used lightly to raise or lower the pitch of an instrument according to my invention. It will be obvious, furthermore, that since in the form shown in Fig. 10 the complex wave generator controls all of the notes of the instrument and all of the tones of an octave would be raised by the same amount, the intervals of the octave would not be as accurate as they were before the raise was made, yet the octave relations would still be maintained and considerable change in pitch could be made before the intervals were noticeably "off."

It is to be understood further, that each octave may have its own complex wave generator or each manual its own complex wave generator in a multi-manual instrument. In such an arrangement I may easily give a stop a slightly different quality in the different octaves. We know, for example, that the quality of the tones produced by many instruments, as, for example, a clarinet, changes greatly throughout their ranges. Accordingly, if we wish to reproduce clarinet tones faithfully on an instrument according to my invention over its entire range, we simply alter the harmonic content of the clarinet stop in the different octaves.

It will be readily understood by those skilled in the art that it is possible with my invention to build an organ-like instrument which will cover the entire range of pitch and timbre with 25 pulse generators or less, and one complex wave generator employing the principle involved in automatic telephone switching. An organist has ten fingers and two feet, so that there never are more than ten keys and two pedals down at the same time. Accordingly, the number of pulse generators in use at a single time is never more than twelve. Using an automatic telephone switching arrangement, when a key or pedal is pressed, it can be made to do three things in sequence, namely, first, pick a pulse generator which is not busy, second, give it the right frequency, and third, connect it to the frequency changer tube so that the tone will sound. When the key is released the tone is stopped either quickly or gradually and the pulses continue at the same frequency until the pulse generator is needed for a different key.

I have noted that the pulse generator will

follow any synchronizing frequency which follows within the audio range of its natural period. For example, if the natural frequency of a pulse generator is 20,000 cycles per second, it will follow any synchronizing frequency between 20,000 and 22,000 cycles per second. This will cover six octaves of tones.

I would also like to point out that I can key to permit the different harmonics in a tone to have different attack and release times or to cause some harmonics to exist only at the time the tone is initiated. This enables me to obtain effects such as the scrape of the bow of a violin, enabling me to obtain the effect of an actual instrument being played.

Referring now to Fig. 11, I have shown diagrammatically the keying arrangement for the instrument assembly shown in Fig. 10. Tubes 181, 182 and 183 are pulse generators connected by conductors 184, 185 and 186 to their corresponding frequency locking oscillators. The vacuum tube 187 is the frequency changer tube, the output of which is connected to the amplifier by conductor 188. The key 189 is in the off position. The keys 190 and 191 are in the sounding position. It will be seen that the sounding of a key impresses the output of its corresponding pulse generator upon the grid 192 of the frequency changer tube, each of the pulse generators being connected in parallel through a respective key to the grid 192. The grid 193 of the tube 187 is subjected to the output of the complex wave generator through conductor 194.

A keying arrangement is illustrated in Figs. 12, 13 and 14, though it is to be understood that any suitable keying means may be employed. The keying arrangement shown is of particular advantage since it will eliminate any clicks or thumps. The coupling is capacitative.

Referring now to Fig. 12, secured to a suitable support 195 adjacent the key board are a plurality of hanger members 196 comprising a pair of arms 197 and 198 terminating in inwardly directed pintles 199 and 200, as can readily be seen by reference to Fig. 13. A housing 201 made of any suitable dielectric material is mounted for rotation on the pintles 199 and 200. Pins 202, 203 and 204 pass through the housing and terminate in flattened heads 205, 206 and 207. The interior periphery of the housing is covered with a layer of dielectric material 208. A body of mercury 209 is contained within the housing. The key proper 210 is pivoted in any suitable manner on a support 211 and carries an extension 212 which is normally slidably mounted in the end of the key. The end of the extension 212 is pivotally secured to the housing at an eccentric point thereon. The action is such that when the key is depressed the housing is rotated around pivots 199 and 200.

In the position shown in Fig. 14, the key is in the off or non-sounding position. It will be noted that in this position the body of mercury 209 capacitatively couples pins 204 and 203. In this position, by reference to Fig. 14, it will be noted that the output of the pulse generator is not fed to the grid 192 but is grounded. As the key is depressed, the housing is rotated and the body of mercury, due to its weight, will remain stationary. In the depressed position, pins 202 and 203 are bridged by the mercury, though separated therefrom by a thin layer of dielectric material 208. This capacitatively couples the two pins 202 and 203 since they terminate in flattened portions which act as the plates of a con-

denser and at the same time uncouples the output of the pulse generator from ground. In this position the output of the pulse generator is coupled to the grid 192 of the frequency changer tube 187. It will be further noted that the coupling and uncoupling is progressive and gradual due to the gradual approach of the mercury to the position of maximum coupling. This enables the tones to sound gradually instead of coming on suddenly with a click or thump. The pin 284 is connected by conductor 213 to ground. The pin 283 is connected by conductor 214 to the plate output of the pulse generator. The pin 282 is connected by conductor 215 to the grid of the frequency changer tube.

From the foregoing it will be readily appreciated that my invention makes it possible to change the fundamental frequency of a complex wave and at the same time maintain the original harmonic content of the complex wave. I have disclosed one means for generating a complex wave harmonically. It is understood, of course, that any suitable electronic means for generating a complex wave may be employed for impression upon the grid of the frequency changer tube.

The human voice is the most versatile and flexible complex wave generator known. Words spoken are made up largely of frequencies harmonically related. Some of the frequencies contained in speech are made with the teeth, throat and parts other than the vocal chords. The vocal chords generate waves rich in harmonics. This harmonic content is controlled by the use of the mouth, the throat, the tongue, the teeth and the lips. A person speaking in a monotone, say with a fundamental frequency of 200 cycles per second, will emit largely frequencies harmonically related to a wave whose frequency is 200 cycles per second. In other words, the vocal chords vibrate in such case at 200 cycles per second and by changing the shape of the oral cavity and the throat resonance to the different harmonics of 200 cycles per second is controlled, imparting different character to the sounds.

Considering further the example of the person speaking in a monotone at 200 cycles per second, the frequencies generated will be 200 cycles per second, 400 cycles per second, 600 cycles per second, 800 cycles per second, and so on. The magnitudes of these harmonics will, of course, vary as the person makes different sounds, but the frequencies will always be 200 cycles per second and multiples thereof as long as the voice continues in the same monotone and disregarding the extra sounds which are not necessarily harmonically related tones.

In carrying out my invention, I may employ the human voice as the source of origin of complex waves whose shape is imparted to an electrical wave whose frequency may be changed. An instrument of this character makes it possible for a musician to play it as an organ having a large variety of tone qualities. It makes it possible for the musician to exercise control over the attack and release of tones. He can make such an instrument, according to my invention, sing and hum as a chorus of voices in which the sounds are words. He can impart delicate shading and slurring to the music. He can make the voices have any tone quality he may desire over the entire pitch range, which range incidentally will be much greater than that of any human voice. He can make such an instrument whistle. An organ in which the human voice is

the origin of the complex wave, and built in accordance with my invention, is shown diagrammatically in Fig. 15. The person whose voice is the origin of the complex wave speaks into a microphone 216 in a monotone. The microphone changes the complex wave into a similar electrical complex wave which is amplified in amplifier 217. The amplified complex electrical wave is fed to a modulator 218, into which, too, is fed a pulse wave from pulse generator 219. The pulse wave has essentially a uniform harmonic content. The output of the modulator will be a large number of frequencies caused by all of the harmonics beating together. Assuming, for example, that the frequency of the pulse is 20,000 cycles per second and only certain of the generated frequencies are desired, the filter 220 will reject the unwanted frequencies and pass only those frequencies caused by the sum of the fundamentals. Considering that the monotone human voice frequency is 200 cycles per second, the sum of the pulse frequency and the voice frequency will be 20,200 cycles per second. The sum of the second harmonics will be 40,400 cycles per second; the sum of the third harmonics will be 60,600 cycles per second, and so on. Those frequencies which pass through the filter make up a complex wave whose fundamental frequency is 20,200 cycles per second.

I recognize that the pulses generated by the pulse generator do not contain all harmonics in equal magnitudes. The filter 220 is so designed that it will attenuate some frequencies which it passes more than others to compensate for the deficiency in the attenuated harmonics. I can control the filter, furthermore, by means operated by the musician in order that the quality of the singing voice issuing from my instrument may be altered if desired by the musician. The complex wave coming from the filter 220 is now treated precisely the same as the complex wave electronically generated. If the musician presses the key for A, having a frequency of 440, then a pulse from the pulse generator 221 generated at a fundamental frequency of 20,660 cycles per second, is fed to the frequency changer 222. The complex wave from the filter is fed through channel 223 to the frequency changer for scanning by the pulse wave as heretofore described. When the pulse wave of 20,660 cycles per second scans a complex wave whose frequency is 20,200 cycles per second, the resulting frequency will be 440 cycles per second, and multiples thereof, assuming, of course, that the filter 220 is properly adjusted.

The series of pulses having an envelope similar to the complex wave being fed to the frequency changer and a wave whose frequency is 440 cycles per second, is fed from the frequency changer through channel 224 to the amplifier 225 and thence to the loud speaker 226 of the instrument.

The modulator 218 is one such as the square-law modulator in order that it does not produce distortion.

Suppose now that a woman musician wishes to speak into the microphone 216 and her voice is pitched higher than 200. Let us say, for example, that it is 400 cycles per second. She merely turns the control on the pulse generator 219 to lower its fundamental frequency to 19,800 cycles per second. This is very simple to do since the pulse generator will oscillate at a frequency controlled by the locking or control oscillator whose frequency can be very simply ad-

justed. With the pulse generator thus adjusted when the woman speaks in a monotone at 400 cycles per second, the harmonics of her voice are added to the harmonics of the pulse giving a fundamental of 20,200, and harmonics of 40,400, 60,600, 80,800, and the like, exactly as was the case when the voice whose fundamental was 200 cycles per second spoke into the microphone. The words can be spoken at any frequency monotone, though preferably not below say 200 cycles per second because of the demands made upon the filter 220 in rejecting unwanted frequencies that are close in frequency to those that it is desired to pass.

In order to insure the musician that his monotone is properly tuned with the pulses from the pulse generator 219, I provide an integrator and rectifier 227, the output of which passes through channel 228 to a cathode ray tube 229, sold under the trade-name "Magic Eye."

If the musician slurs his monotone up, say 20 cycles per second, making it 220 instead of 200, and the pulse generator 219 is left at 20,000 cycles per second, then the frequency "A" coming from the loud speaker will slur up from 440 to 460, making it possible for the musician to slur tones. This, of course, must be used by him with care for if he is playing a chord which he slurs up 20 cycles per second from 200 cycles per second, he will add 20 cycles per second to all of the tones in the chord, tending to upset the harmonious relation that these tones previously had. This factor, furthermore, enables the musician to obtain weird or "blue" effects not heretofore possible. The slurring, furthermore, can be readily tolerated within limits and in fact may be beneficial in tending to temper the exacting of pitch which is inherent in electronic instruments, and which ultimately makes them tiresome.

If the musician wishes to play the instrument without supplying a complex wave to the microphone, he merely turns the frequency control on the pulse generator 219 so that its fundamental frequency is say 20,200 cycles per second, or any other predetermined frequency, and the instrument is then ready to be played with the pulse itself as the complex wave. Its harmonic content can be controlled by the controls on the filter 220.

I may have a console of more than one manual with a complex wave generator for each manual. With this arrangement the musician can play singing or humming voices on one manual and the accompaniment on the other manual or manuals. Where two or more manuals are used, each manual may be arranged as shown in Fig. 15, so that two people can speak into the two microphones and the singing controlled on different manuals enabling the control of the different voices to be maintained separately. Likewise, the pulse generator 219 may be used on one manual and the other manual can employ the microphone as the origin of the complex wave.

It will be clear to those skilled in the art that many variations are possible. The microphone or a special vibration pick-up may be used to pick up tones from a violin or other instrument. If the violin is used, one tone is constantly bowed. This may be done mechanically if desired. The musician keys the instrument to produce the music. A single stretched string, therefore, may be employed which may if desired be struck as in a piano or plucked. Its tone may then be

picked up by the microphone, making it possible to obtain percussion effects. Similarly, chimes, bells and the like may be used as the origin of the complex wave. Countless effects may be achieved by controlling the harmonic content in filter 220.

I have mentioned above that words spoken were not made up entirely of harmonically related frequencies. The vowel sounds of the voice are made up of harmonically related frequencies and these sounds really make vocal music. By proper filtering the unharmonic sounds may be reinserted after the vowels have gone through the frequency changer.

15 Care must be taken in an instrument using an independent sound source and a microphone, that sounds do not feed back from the loud speaker to the microphone causing a howl, such as is experienced in public address systems. Directional microphones that are relatively insensitive to anything but sounds made directly into them may be employed.

By means of my invention I am enabled to give the technique of known instruments such as the pipe organ, piano, chimes, bells, harpsichord, violin, and the like, as well as synthetic tones and the human voice. In using the human voice as the origin of the complex wave, the musician simply speaks in a monotone into the microphone. The keys determine the pitch so that the organ may sing soprano even though a man plays it. The tones may be initiated and stopped either with the keys or by the musician's voice, or both. It will be understood, of course, that if the musician does not speak, nothing comes out of the organ though the keys may be pressed. Similarly, if the musician is speaking and the keys are not pressed, no sounds will be emitted from the loud speakers of the organ. If two keys are pressed while words are voiced by the musician, the organ will produce two different pitches of the same voice, so that a single musician may sing a duet, quartet, and the like, employing but a single voice as the origin of the complex wave. By means of the filter, it is possible to reproduce the musician's voice with fidelity or to give it another timbre by emphasizing some harmonics and attenuating others.

50 If two people talk into the microphone at the same time it will serve as two complex wave generators, even though they say different words the organ will produce these words in singing if the keys are played properly. Any number of voices may be used if desired, adding richness due to human inaccuracies in keeping pitch.

It will be seen that I have accomplished the objects of my invention. An instrument according to my invention is all electronic and may 60 employ vacuum tubes which are dependable, inexpensive, uniform and have long life. The circuits are made principally of inexpensive resistors and condensers and are as a whole not critical in their adjustments, so that they can be serviced by a radio repair man without special apparatus. Any tone quality may be produced. Standard stop controls may be used or, if desired, harmonic controls for synthesizing tones to suit individual musicians, or a combination of 70 both may be used. A large number of different stops is easily obtainable. Keying does not cause objectionable transients, and one method of keying offers two attack times, two release times and second touch. All of the tone producing circuits are made of standard radio parts which

are produced in mass production for the radio industry, making them available for the manufacture of my instrument at a low cost.

Every tone produced has true harmonics and not tempered harmonics, yet the tones may be synthesized in a simple manner. Every tone in the scale may have exactly the same quality or the harmonic content may be made to vary from octave to octave to produce substantially the same quality variations as other musical instruments do. The efficiency of the instrument is increased as the number of stops is increased and as the number of manuals is increased. All of the tones may be caused to slur up or down by a single control, making trombone smears and innumerable effects possible. The variation in pitch of all of the tones in a simple manner makes it possible to tune my instrument with a xylophone, piano or other instrument not at International pitch.

The entire instrument may be given a vibrato or combined vibrato and tremolo with a single vibrator or one tube. The vibrato may be applied to individual manuals or, if desired, to each interval of the octave. The vibrato may be slightly different on each to give an enrichening effect. When the vibrato is applied to the complex wave generator, a celeste effect is obtained.

The human voice or other complex wave generating means may be employed as the origin of the complex waves, providing an instrument which will challenge all of the talent and imagination which musicians possess.

It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. A method of generating musical tones having a desired wave form and desired audible frequency comprising the steps of generating an electric wave having the desired wave form at a frequency relatively high with respect to the desired audible frequency, generating a succession of electrical impulses, impressing said impulses upon said electrical wave at a frequency which will produce an electrical wave having a component which is of the desired wave form and desired audible frequency, and converting said component into the desired musical tone.

2. A method of generating musical tones including the steps of generating a complex electrical wave of a predetermined wave form at a super audio frequency, generating a succession of pulses at a frequency different from the frequency of said complex wave by a number of cycles equal to the desired pitch, impressing said pulse wave upon said complex wave to produce an electrical wave having a component which is of the form of the complex wave and at a frequency of the desired pitch, and converting said component into the desired musical tone.

3. An electronic musical instrument including in combination a complex wave generator for generating a wave of a predetermined wave form at a super audio frequency, an oscillator for generating a series of positive pulses at a frequency different from the frequency of said com-

plex wave by a number of cycles equal to the pitch of a desired musical tone, means for impressing said pulses upon said complex wave to produce a series of pulses having an envelope which is a wave having the wave form of the complex wave and a frequency which is that of the desired pitch within the audible range, means for amplifying the electrical wave of audio frequency, and means for converting said electrical wave into a sound wave of the desired pitch and timbre.

4. An electronic instrument including in combination a complex wave generator for generating a complex wave of a predetermined wave form at a super audio frequency, a plurality of pulse generators for generating a plurality of series of impulses at respective frequencies different from the frequency of said complex wave by respective amounts equaling the frequency of various notes in a musical scale, key controlled means for selectively impressing said impulses upon said complex wave, said key controlled means including a thermionic mixer tube the output of which includes an electrical wave having the wave form of the complex wave and a frequency within the audio range determined by the keys, means for amplifying the output of said mixer tube, and means for converting the amplified electrical wave of audio frequency to a sound wave of the desired pitch and timbre.

5. An electronic instrument including in combination a vacuum tube connected in an oscillating circuit to produce a continuous wave rich in harmonics and at a predetermined super audio frequency, a filter having a plurality of parallel tuned circuits, tuned respectively to the fundamental and harmonics of said continuous wave, means for controlling the amounts of the fundamental and respective harmonics passed by said filter, the output of said filter being a continuous wave of a predetermined wave form at a predetermined super audio frequency, vacuum tube means for generating a series of positive impulses at a super audio frequency higher than said complex wave frequency by an amount equal to the frequency of a desired musical note, a thermionic mixer tube having a grid, means for impressing the continuous complex wave upon the grid of said tube, key controlled means for impressing the series of pulses upon the grid of said tube to produce an electrical wave having the form of the complex wave and a frequency equal to the desired musical pitch, means for amplifying said electrical wave of the desired wave form and musical frequency, and means for converting the amplified electrical wave into a sound wave of the desired timbre and pitch.

6. An electronic musical instrument including in combination means for generating a complex wave of predetermined wave form at a predetermined super audio frequency, means for generating a series of positive electrical pulses at a frequency higher than the frequency of said complex wave by an amount equal to a desired musical pitch, a thermionic mixer tube, means for feeding said complex wave to said thermionic mixer tube, key controlled means for selectively feeding said series of positive pulses to said mixer tube, means for generating a vibratory continuous wave at a low frequency, means for selectively feeding the low frequency vibratory wave to said thermionic mixer tube whereby the output of said mixer tube will comprise an electrical wave of the wave form of said complex wave and at a frequency of the desired musical pitch.

varying slightly in pitch at the frequency of said vibratory wave, means for amplifying the output of said mixer tube, and means for converting the amplified electrical wave into a vibrating sound wave of the desired pitch and timbre.

7. An electronic musical instrument including in combination means for generating a continuous complex wave of a predetermined wave form at a super audio frequency, a thermionic mixer tube, means for feeding said complex wave to said mixer tube, a plurality of thermionic tubes connected in respective circuits for producing a series of sharp positive electrical pulses at respective frequencies higher than the frequency of said complex wave by respective amounts equal to respective pitches of musical notes, a plurality of keys, a plurality of dielectric housings, separate means for mounting said housing for rotation in response to the actuation of said keys, three conductors entering each of said housings, means for electrically connecting one of said conductors to the output of a pulse generator, means for connecting the second of said conductors to ground, means for connecting the third of said conductors to said thermionic mixer tube, a body of mercury in said housing, said body of mercury normally capacitatively coupling the output of a pulse generator to ground, the construction being such that upon the actuation of its respective key, a housing will rotate to move said body of mercury to a position capacitatively coupling the output of said pulse generator to said mixer tube to produce an electrical wave having the wave form of said complex wave at a selected musical frequency, means for amplifying the output electrical wave of the mixer tube, and means for converting said amplified wave into a corresponding sound wave having the desired pitch and timbre.

8. In an electronic musical instrument a microphone adapted to convert sound waves into electrical waves, thermionic tube means for creating a plurality of positive pulses at a predetermined frequency, means for modulating said pulses by said electrical wave corresponding to said sound wave, the output of said modulating means being a series of pulses having an envelope of the wave form of said sound wave and at a predetermined frequency equal to the frequency of said pulses plus the frequency of said sound wave, means for generating a second series of pulses of uniform height and at a frequency higher than the output frequency of said modulator by an amount equal to the pitch of a desired musical tone, a thermionic mixer tube, means for feeding the output of said modulator and the output of said second pulse generator to said thermionic mixer tube to produce an electrical wave having the wave form of said sound wave and at a frequency equal to the pitch of the desired musical tone, means for amplifying the output of said mixer tube, and means for converting the amplified wave into a sound wave of the wave form of the original sound wave and at the desired pitch.

9. An electronic musical instrument including in combination a microphone for converting a sound wave into a corresponding electrical wave of a predetermined wave form and pitch, means for amplifying said electrical wave, means for generating a series of electrical pulses at a super audio frequency, means for modulating said series of pulses by said amplified microphone electrical wave to produce a modulated series of

impulses at a frequency which is the sum of the frequency of said pulses and the frequency of said sound waves, a filter for rejecting undesired frequencies and harmonics thereof, the output of the filter being a modulated series of pulses of a predetermined frequency and a predetermined wave form, a second pulse generator for creating a plurality of electrical impulses at a frequency higher than the filtered pulse frequency by an amount equal to the pitch of a musical tone, a thermionic mixer tube, means for feeding the output of said filter and the output of said second pulse generator to said mixer tube to produce an electrical wave having the wave form of the filtered wave and a frequency equal to the pitch of the desired musical tone, means for amplifying the mixer tube output wave, and means for converting said amplified electrical wave into a sound wave having the form of said filtered wave and a pitch equal to the desired musical tone.

10. An electronic musical instrument as in claim 9 in which there are a plurality of second pulse generators for generating a plurality of series of pulses at frequencies higher than the filter pulse frequency by respective amounts equal to the frequency of the notes of a musical scale, and key control means for selectively impressing the outputs of the respective pulse generators upon said mixer tube.

11. In an electronic musical instrument, means for generating a complex wave at super audio frequency, including in combination an oscillator producing a continuous wave rich in harmonics at the desired frequency, a filter including a plurality of parallel tuned circuits tuned respectively to the fundamental and various harmonics of said frequency, resistors connected across said parallel tuned circuits, means for selectively shunting a portion of the respective resistors whereby to control the harmonic content of the wave passed by the filter, key controlled means for changing the frequency of the filtered wave to a predetermined frequency within the audio range, means for amplifying the audio frequency electric wave, and means for converting the amplified electric wave into its corresponding sound wave.

12. An electronic musical instrument as in claim 11 in which said shunting means comprises a plurality of switches, and common means for operating all of the switches simultaneously.

13. An electronic instrument including in combination an oscillator connected in a circuit to produce a continuous wave rich in harmonics at a predetermined super audio frequency, a filter connected across the output of said oscillator comprising a plurality of parallel tuned circuits tuned respectively to the fundamental and the various harmonics of said predetermined frequency, voltage dividers across each of said parallel tuned circuits, said voltage dividers governing the respective harmonic components of the output wave of the filter, a plurality of stop means operable by the musician for operating said voltage dividers to produce predetermined complex waves, key controlled means for selectively changing the frequency of the filtered complex wave to a predetermined frequency within the musical range, and means for converting the electrical wave within the musical range to a musical note of a pitch determined by the key controlled means and a timbre controlled by the stop means.

14. An electronic musical instrument including

in combination means for generating a continuous complex wave at a super audio frequency, means for sampling said complex wave instantaneously at a super audio frequency higher than the frequency of said complex wave by an amount equal to the pitch of a musical note, the output of said sampling means being a series of pulses having an envelope whose form is that of the complex wave and whose frequency is that of the musical note, means for amplifying said envelope wave, and means for converting the amplified envelope wave to an acoustic wave having a wave form substantially identical to the wave form of said complex wave and at a pitch of said musical note.

15. An electronic instrument as in claim 14 in which said sampling means comprises a cathode ray tube having a collector ring and a probe, means for impressing the output of said complex wave generator upon the grid of said cathode ray tube, means for impressing a sine wave to the vertical and horizontal deflecting plates of said cathode ray tube with a 90 degree relationship, the frequency of said sine wave being higher than the frequency of said complex wave by an amount equal to the pitch of said musical note.

16. A musical instrument as in claim 14 in which said sampling means comprises a thermionic mixer tube, a feed-back oscillator adapted to produce sharp positive pulses at a frequency higher than the frequency of said complex wave by an amount equal to the pitch of said musical note, said mixer tube being provided with two grids, means for impressing the output of said complex wave generator upon one of said grids, and means for impressing the output of said pulse generator upon the other of said grids.

17. An electronic musical instrument including in combination a feed-back oscillator connected in circuit to produce a plurality of sharp pulses of relatively short duration at a predetermined frequency, a complex wave generator for producing a complex wave at a super audio frequency below the frequency of the pulse generator by an amount equal to the pitch of a musical note, a frequency changer tube having a plate and two grids, means for impressing the output of said pulse generator on one of said grids, means for biasing the plate current to cutoff except upon the application of said pulses of short duration, means for applying the output of said complex wave generator to the other of said grids whereby said tube may act as a detector receiving an unmodulated carrier wave and the effect of said pulse is to scan or sample said complex wave to produce an electrical wave having the form of said complex wave but at the frequency of said musical note, means for amplifying the output of

said frequency changer tube, and means for converting the amplified wave to an acoustic wave of the desired pitch and timbre.

18. An electronic instrument including in combination a vacuum tube connected in an oscillating circuit to produce a continuous wave rich in harmonics and at a predetermined super audio frequency, a filter having a plurality of parallel tuned circuits, tuned respectively to the fundamental and harmonics of said continuous wave, means for controlling the amounts of the fundamental and respective harmonics passed by said filter, the output of said filter being a continuous wave of a predetermined wave form at a predetermined super audio frequency, vacuum tube means for generating a series of positive impulses at a super audio frequency different from said complex wave frequency by an amount equal to the frequency of a desired musical note, a thermionic mixer tube having a grid, means for impressing the continuous complex wave upon the grid of said tube, key controlled means for impressing the series of pulses upon the grid of said tube to produce an electrical wave having the form of the complex wave and a frequency equal to the desired musical pitch, means for amplifying said electrical wave of the desired wave form and musical frequency, and means for converting the amplified electrical wave into a sound wave of the desired timbre and pitch.

19. In an electronic musical instrument a microphone adapted to convert sound waves into electrical waves, thermionic tube means for creating a plurality of positive pulses at a predetermined frequency, means for modulating said pulses by said electrical wave corresponding to said sound wave, the output of said modulating means being a series of pulses having an envelope of the wave form of said sound wave and at a predetermined frequency equal to the frequency of said pulses plus the frequency of said sound wave, means for generating a second series of pulses of uniform height and at a frequency different from the output frequency of said modulator by an amount equal to the pitch of a desired musical tone, a thermionic mixer tube, means for feeding the output of said modulator and the output of said second pulse generator to said thermionic mixer tube to produce an electrical wave having the wave form of said sound wave and at a frequency equal to the pitch of the desired musical tone, means for amplifying the output of said mixer tube, and means for converting the amplified wave into a sound wave of the wave form of the original sound wave and at the desired pitch.

EARLE L. KENT.
